[57] CLAIM

The ornamental design for a putter type golf club head, as shown and described.

DESCRIPTION

FIG. 1 is a front perspective view of a putter type golf club head showing my new design.

FIG. 2 is a bottom perspective view thereof.

FIG. 3 is a top plan view thereof.

FIG. 4 is a front elevational view thereof; the rear elevational view being a mirror image.

FIG. 5 is an end elevational view thereof.

FIG. 6 is a bottom view thereof; and,

FIG. 7 is an end elevational view taken from the opposite side of FIG. 5.

The broken lines showing a fragmented shaft are for illustrative purposes only and form no part of the design.
